UNITED STATES PATENT OFFICE.

PERCY LAW JOHNSON, OF KINETON, ENGLAND.

APPARATUS FOR USE IN DISPLAYING ADVERTISEMENTS, NOTICES, PICTURES, OR THE LIKE.

Application filed November 25, 1925. Serial No. 71,416.

This invention relates to apparatus for use in displaying advertisements, notices, pictures, or the like, in which the characters, pictures, signs, or the like, are carried on 5 levers, bars, bands, or the like, and are immersed in an opaque liquid contained in a tank with a transparent front face or window; and means are provided for independent operation of the several sets of levers, 10 bands, or sets of bands, or the like, which carry the characters, or the like, in order to cause the said characters or the like to move to or from the said window or the like for the purpose of rendering them visible or 15 invisible as desired, such means comprising a revolvable member for each set of levers, band, set of bands, or the like, the said member functioning to move forward against the window all the characters or the like 20 which are under its control and to hold the same against the window as long as is desired.

Apparatus as above set forth is described in the specification of my British Patent No. 25 226,040.

The present invention may in brief be said to consist in a construction and arrangement of apparatus of the nature of that referred to above. This construction and arrangement 30 will be described in the following specification: the invention will be defined in the annexed claims.

The accompanying drawings illustrate an advertising sign constructed in accordance 35 with the present invention.

In these drawings Figure 1 is a front elevation with part of the sign broken away in order to reveal the driving mechanism.

Figure 2 is a side elevation.

Figure 3 is a side sectional elevation on the line X—X of Figure 1.

Figure 4 shows, on an enlarged scale, the upper part of the mechanism shown in Figure 3.

Figure 5 is a front elevation, on the same scale, of the mechanism shown in Figure 4.

Figure 6 is a side sectional elevation of the four cams only, taken on the line X—X of Figure 1 but on an enlarged scale.

50 In the advertising sign shown in the drawings one side of a tank *a* consists of a frame *b* carrying a sheet of glass *c*, the whole assembly forming a liquid-tight tank having a

window. An opening *d* in the top of the tank is closed by a lid *e* which renders the 55 tank vapour tight.

Shafts *f*, equal in number to the number of rows of characters in the sign—in this case four—are supported, one vertically above the other, in the tank *a*. Each shaft 60 is parallel both to the window *c* and to the bottom of the tank *a*, and is carried in bearings in the walls *h* of the tank. One end of each shaft *f* projects through the same side of the tank *a* and carries a chain wheel *i*. A 65 chain *k* passes over the four chain wheels *i* and also over a fifth chain wheel *m* which is continuously driven by an electric motor *n*, secured to the back of the tank *a*, by means of a belt *s* and reduction gearing *t* 70 and *u*.

Each of the shafts *f* carries two cams which are formed by cutting away part of the surface of a hollow cylinder *l*. Each cylinder *l* is supported at its ends on discs 75 2, secured to the corresponding shaft *f*. A portion of the surface of each cylinder is cut away so as to leave one edge 3 parallel to the axis of the shaft *f* while the other edge describes a helix with respect to the 80 axis of the shaft. The edges 3 and 4 form cams by means of which the characters of the sign are moved, in the manner herein-after described.

A removable frame, consisting of two parallel bars *5*, arranged vertically and connected and spaced apart by rods *6*, is supported inside the tank *a*. The distance between the bars *5* is such as to allow of the frame being slid into and out of the tank *a* through 90 the opening *d* in its top. The lower ends of the bars *5* have notches *7* which engage with studs *8* on the inside of the walls *h* of the tank *a*. The ends of the uppermost rod 6 are extended and the extensions *9* slide in 95 grooves *10* in blocks *11* carried on the inside of the walls *h* of the tank *a*.

There are as many rods *6* as there are shafts *f* and the studs *8* and grooves *10* support and position the frame *5* inside the tank 100 *a* so that each rod *6* is in front of and parallel to, but higher than, the corresponding shaft *f*.

A number of levers *12*, each of which corresponds to one character of the sign, are 105 carried loosely on sleeves *13*, which sleeves

are carried on, and grip lightly, the rods 6. The number of levers carried on each rod 6 is equal to the number of characters which may be rendered visible in the row corresponding to that rod. The levers 12 are allowed to depend vertically from the rods 6 and each lever carries a character at its lower end and is provided, also at its lower end and on the side nearer to the cylinders 1 with a projection 14.

The characters 15 are formed in relief on blocks 16, the relief being of a depth greater than the distance through which objects can be seen through the opaque liquid. Each block 16 is secured to a plate 17 which is attached to the lower end of one of the levers 12. The back of each block 16 is grooved so that it can be slidden on to the correspondingly formed plate 17. A projection 18 on the top of the back of each block 16 engages with the top of the plate 17 when the character has reached its correct position with regard to the plate 17. In the case of characters such as periods, commas, and the like, which appear only above or below the horizontal centre line of the row of characters, a pin 19, having the same colour as the opaque liquid, is attached to the block 16 on which the character is formed so that it comes into contact with the window c and ensures that the face of such character is brought truly against the window.

Each plate 17 has a pair of parallel extensions 20 which embrace the end of the corresponding lever 12. A pin 21 passes through the end of the lever and through the two projections. The hole in the lever through which the pin 21 passes is enlarged so as to permit of a slight relative movement between the lever 12 and the plate 17. The extensions 20 serve to keep the characters in a vertical position as well as a means of attaching the plates 17 to the levers 12. A spring 22 is interposed between each plate and its corresponding lever and is housed in a recess 23 formed in the extensions and lever.

The gap between the edges 3 and 4 at the left-hand end of the uppermost cylinder 1 is sufficiently large to allow of the entry of the projections 14 on the levers 12. At the right-hand end of this cylinder the gap has increased by an amount corresponding to the circumferential angle described by the helical edge 4. In the other cylinders the gap at the left-hand end is equal to that at the right-hand end of the cylinder immediately above it. The relative positions of the cylinders 1 upon the shafts f is clearly shown in Figure 6, from which it will be seen that all the edges 3, each of which is parallel to the axes of the shafts f, are arranged to pass the projections 14 on the levers 12 simultaneously.

The operation of the mechanism of the above-described advertising sign is as follows:—

Assume that the parts are at rest and that the projections 14 on all the levers 12 are in the position shown in the lower part of Figure 4, i. e. entering into the space between the edges 3 and 4 of the cylinders 1. None of the characters is in contact with the window c and all the characters are consequently invisible. When the driving motor n is started the shafts f are simultaneously caused to rotate continuously, the uppermost and lowermost shafts in a counter-clockwise direction and the other two shafts 80 clockwise, as indicated by the arrows in Figures 3, 4 and 6.

The helical edge 4 of the uppermost cylinder 1 engages the projections 14 on the levers 12 of the uppermost row of characters. The projections 14 ride on to the surface of the cylinder 1 and cause the levers 12 to pivot about the rod 6 and to bring the characters successively into contact with the window c, thus rendering them successively 90 visible from left to right when the helical edge 4 of the uppermost row has caused the last letter of that row to appear, the helical edge of the cylinder corresponding to the second row will be about to cause the first 95 character in that row to appear. This will be evident from a study of Figure 6 and from the explanation given above. When all the characters of the second row have 100 successively appeared those of the third row will follow and these will in turn be followed by the characters of the fourth row. All the characters are now visible and remain visible until the projections 14 ride over the edges 3 of the cylinders 1 and 105 enter the spaces in the cylinders, which they do simultaneously. The levers 12 thereupon fall backwards by gravity and all the characters are simultaneously withdrawn from contact with the window c and therefore simultaneously rendered invisible. They remain invisible until, on continued rotation of the cylinders c, the above-described cycle 110 of operations re-commences and continues to be repeated until the driving motor n is 115 stopped.

By varying the relative positions of the edges 4 and/or changing the direction of rotation of the shafts f, the rows of letters may be made to appear in any desired order 120 and the letters in each row may be made to appear either simultaneously or successively as desired. For instance by reversing the direction of rotation of the shafts f in the above described sign simultaneous appearance and successive disappearance of the letters may be caused, the last letter in the lowermost row being the first to be rendered invisible.

When it is desired to change the adver- 130

tisement the frame 5—which frame carries the characters forming the advertisement—is removed from the tank through the opening *d*. The blocks 16 are then removed from 5 the plates 17 and other blocks, carrying the characters forming a new advertisement, substituted.

The sleeves 13, on which the levers 12 are carried, are easily slidable along the rods 6 10 and thus allow the levers 12 and the characters which they carry to be readily spaced as desired along the rods 6.

Having thus described my invention, what I claim as new and desire to secure by Letters Patent is:—

1. Apparatus for displaying advertisements, notices, pictures and the like including a tank, an opaque liquid in said tank, a window in said tank, carriers, means for supporting said carriers in rows in said tank, display matter carried on said carriers, and means for causing the said carriers to be moved to and from the said window for the purpose of rendering the said display matter 25 visible or invisible, said last mentioned means comprising a revolvable member for each row of carriers, a cylindrical surface on each of said revolvable members, said cylindrical surface being cut away to provide a gap extending longitudinally of said member (that is, parallel to its axis of revolution), means whereby said revolvable members are connected together, means whereby said revolvable members are continuously and simultaneously driven, and projections on the said first-mentioned means, both edges of said gap in said cylindrical surface on each member, and the surface of said member, co-acting with said 30 projections in the corresponding row to move said display matter into contact with said window and to retain it there temporarily and then to allow of its withdrawal therefrom.

2. Apparatus for displaying advertisements, notices, pictures and the like including a tank, an opaque liquid in said tank, a window in said tank, carriers, means for supporting said carriers in rows in said tank, display matter carried on said carriers, and means for causing the said carriers to be moved to and from the said window for the purpose of rendering the said display matter visible or invisible, said last-mentioned means comprising a revolvable member for each row of carriers, a cylindrical surface on each of said revolvable members, said cylindrical surface being cut away to provide a gap extending longitudinally of said member (that is, parallel to its axis of revolution), means whereby said revolvable members are connected together, means whereby said revolvable members are continuously and simultaneously driven, and projections on the said first-mentioned

means, both edges of said gap in said cylindrical surface on each member, and the surface of said member, co-acting with said projections in the corresponding row to move said display matter into contact with said window and to retain it there temporarily and then to allow of its withdrawal therefrom, the arrangement of gaps in the said surfaces on said members with respect to one another being such that the several rows of display matter are rendered visible in any desired order.

3. Apparatus for displaying advertisements, notices, pictures and the like including a tank, an opaque liquid in said tank, a window in said tank, carriers, means for supporting said carriers in rows in said tank, display matter carried on said carriers, and means for causing the said carriers to be moved to and from the said window for the purpose of rendering the said display matter visible or invisible, said last-mentioned means comprising a revolvable member for each row of carriers, a cylindrical surface on each of said revolvable members, said cylindrical surface being cut away to provide a gap extending longitudinally of said member (that is, parallel to its axis of revolution), a helical edge to said gap, means whereby said revolvable members are connected together, means whereby said revolvable members are continuously and simultaneously driven, and projections on the said first-mentioned means, both edges of said gap in said cylindrical surface on each member, and the surface of said member, co-acting with said projections in the corresponding row to move said display matter into contact with said window and to retain it there temporarily and then to allow of its withdrawal therefrom, the arrangement of gaps in the said surfaces on said members with respect to one another being such that the several rows of display matter are rendered visible in any desired order.

4. Apparatus for displaying advertisements, notices, pictures and the like including a tank, an opaque liquid in said tank, a window in said tank, carriers, means for supporting said carriers in rows in said tank, display matter carried on said carriers, and means for causing the said carriers to be moved to and from the said window for the purpose of rendering the said display matter visible or invisible, said last-mentioned means comprising a revolvable member for each row of carriers, a cylindrical surface on each of said revolvable members, said cylindrical surface being cut away to provide a gap extending longitudinally of said member (that is, parallel to its axis of revolution), a helical forward edge to said gap, a straight-rearward edge to said gap, means whereby said revolvable members are connected together, means whereby said re-

2
volvable members are continuously and simultaneously driven, and projections on the said first-mentioned means, both edges of said gap in said cylindrical surface on each member, and the surface of said member, co-acting with said projections in the corresponding row to move said display matter into contact with said window and to retain it there temporarily and then to allow of its withdrawal therefrom, the arrangement of gaps in the said surfaces on said members with respect to one another being such that the several rows of display matter are rendered visible in any desired order.

5. Apparatus for displaying advertisements, notices, pictures and the like including a tank, an opaque liquid in said tank, a window in said tank, carriers, levers for supporting said carriers in rows in said tank, display matter carried on said carriers, and means for causing the said levers to move said carriers to and from the said window for the purpose of rendering the said display matter visible or invisible, said means comprising a revolvable member for each row of carriers, a cylindrical surface on each of

said revolvable members, said cylindrical surface being cut away to provide a gap extending longitudinally of said member (that is, parallel to its axis of revolution), a helical forward edge to said gap, a straight-rearward edge to said gap, a chain wheel on each of said revolvable members, a chain passing over said chain wheels, an electric motor continuously driving said chain, and projections on said levers, both edges of said gap in said cylindrical surface on each member, and the surface of said member, co-acting with said projections in the corresponding row to move said display matter into contact with said window and to retain it there temporarily and then to allow of its withdrawal therefrom, the arrangement of gaps in the said surfaces on said members with respect to one another being such that the several rows of display matter are rendered visible in any desired order and are rendered invisible simultaneously.

I hereby sign my name to this specification.

PERCY LAW JOHNSON.
